UNITED STATES PATENT OFFICE.

WALTER H. SMITH, OF WILKINSBURG, PENNSYLVANIA, ASSIGNOR TO WESTINGHOUSE ELECTRIC & MANUFACTURING COMPANY, A CORPORATION OF PENNSYLVANIA.

PROTECTIVE SYSTEM FOR MOTORS.

Application filed June 1, 1925. Serial No. 34,066.

This invention relates to systems of control for motor-generator sets and more particularly to control systems for motor-generator sets of the type used for propelling vehicles.

The object of the invention, generally stated, is the provision of a control system for motor-generator sets that shall be simple and positive in operation and economically manufactured and installed.

A more specific object of the invention is to insure the rotation of a motor-generator set at the proper pull-in speed, before the closing of the motor circuits.

15 A further object of the invention is to provide for the automatic closure of the motor circuits when the motor reaches a predetermined pull-in speed.

Other objects of the invention will in part be obvious and in part appear hereinafter.

The invention, accordingly, is disclosed in the embodiment thereof shown in the accompanying drawing and comprises the combination of elements and arrangement of parts that will be exemplified in the system hereinafter set forth and the scope of which will be indicated in the claims.

For a fuller understanding of the nature and objects of the invention, reference should be had to the following detailed description taken in connection with the accompanying drawing, which is a diagrammatic view of a control system arranged in accordance with this invention.

35 Referring now to the drawing, a motor-generator set is shown generally at 10. As illustrated, the generator 11 is mechanically connected to the motor 12 in any suitable manner, such, for example, as by the provision of a common shaft.

During operation, the motor 12 is supplied from any suitable source of alternating current power through the main supply conductors 13. Preferably, these conductors 13 lead from a transformer that is mounted on the vehicle and energized through a pantograph that contacts with the main trolley conductor.

50 It will be readily understood that if the motor 12, while at rest, is connected across the main supply conductors, it will take a heavy current, which, if continued for any considerable length of time, may greatly damage the windings. Consequently, it is desirable to rotate the motor at some prede-

termined speed at which it will build up, when connected across the line, a counter electromotive force sufficient to prevent the flow of an excessive current.

In the embodiment illustrated, one terminal of the motor 12 is connected to one of the supply conductors 13, through a blade of a two-pole switch 14, which hereinafter will be called the motor-generator switch, in order to distinguish it from other switches. The other terminal of the motor is connected to the other supply conductor through a contact member 20 of a relay switch shown generally at 16.

As will be observed, the relay 16 comprises a series coil 19 and a shunt coil 21, which are mounted on a common core 22 and have their adjacent terminals connected. The movable contact member 20 is pivotally mounted and disposed for actuation to its closed position through the energization of the coils 19 and 21. Another contact member 23 is mounted in alinement with an arm 25, which is carried by the contact member 20 and is normally retained closed by a spring 24.

Since the contact member 20 is connected in the circuit of the motor 10, the motor cannot be connected across the line until the coils 19 and 21 are sufficiently energized to close the contact member 20. Consequently, by connecting the coils 19 and 21 for differential action, when the motor 12 is rotated by the generator 11, as will be explained hereinafter, the resultant energization of the coils may be varied directly as the speed and the counter-electromotive force of the generator 11 operated as a motor. Therefore, as will be readily understood, the motor circuit may be kept open until the motor reaches a predetermined pull-in speed.

In order to rotate the motor 12 to build up a counter electromotive force when connected across the line, the generator 11 is connected across any suitable source of electrical energy and operated as a motor. The power source used in this case is a storage battery 17 of the type usually provided on electrically-operated motor vehicles for supplying lighting systems and the like.

As shown, the negative pole of the battery 17 is connected to the negative terminal of the generator through one blade of the motor-generator switch 14. The connection

between the positive pole of the battery and the positive terminal of the generator is through the series coil 19 and is controlled by a contactor 18.

The contactor 18 is of a well-known type and comprises a contact plate 20 that is disposed to bridge the contact fingers 31 upon the energization of a coil 30. In this system, the coil 30 of the contactor is arranged for connection across the supply conductors 13 by the closing of the motor-generator switch 14. Further description of this contactor 18 is considered unnecessary, since it is of a well-known type and is not a part of this invention.

One of the contact fingers 31, which are bridged by the contact plate 20 when coil 30 is energized to close switch 18, is connected through conductor 32 to the positive conductor of train line 28 and the adjacent contact finger is connected to the positive terminal of the battery 17 through conductor 33 and one blade of a two-pole battery switch 15. Another of the contact fingers 31 is connected through conductor 27 to the junction-point of the series and shunt coils 19 and 21, respectively.

Accordingly, upon closing the motor-generator switch 14 and the battery switch 15, the contactor 18 is actuated and a circuit is established from the positive terminal of the battery through battery switch 15, conductor 33, contact fingers 31, which are bridged by the plate 20, where the circuit divides, one branch including coil 19 of the relay 16, generator 11 and thence to the negative terminal of the battery through one blade of the motor-generator switch 14. Thus, the generator 11 is initially connected across the battery 17 and operated as a motor to drive the motor 12.

Since one terminal of the shunt coil 21, as set forth above, is connected to the contact fingers 31 by the same lead as the series coil 19 and the other terminal is connected through the contact member 23 to the negative pole of the battery 17, an energizing circuit for the shunt coil is completed when the contactor 18 is actuated.

As will be observed, the coils 19 and 21 are wound in the same direction on the core 22. Consequently, when the coils are energized from a common conductor 27 connected to their point of juncture, the current flowing in the coils passes in opposite directions about the core 22, giving a differential magnetizing action. The coils are so proportioned that upon the initial energization, they are nearly balanced. However, the generator 11, when operated as a motor, builds up a counter-electromotive force tending to reduce the flow of current in the series coil.

As the speed of the generator operating as a motor is increased, the counter-electromotive force developed further decreases the

flow of current through the series coil 19, thereby unbalancing the magnetizing effect of the series and shunt coils. Finally, if the voltage of the battery is sufficient to drive the generator, operating as a motor, at a speed great enough to develop a counter-electromotive force that neutralizes the magnetizing effect of the coil 19, then the shunt coil, being unopposed, causes a sufficient magnetization of the core 22 to effect closure of the relay 16.

When the motor 12 is rotated at proper pull-in speed and connected across the main source of supply by the closure of relay 16, the counter-electromotive force immediately generated will prevent the flow of an excessive current. Further, the above-described circuits provide means for preventing connection of the motor 12 across the main source of supply until it is rotating at the required pull-in speed, thereby requiring a minimum expenditure of energy by the battery 17, since the motor 12 is not operated as a generator.

As will be observed, the resistor 26 is short-circuited by the contact member 23 when the latter is in its closed position. Consequently, when the relay 16 is operated to close the motor circuit, the contact member 23 is actuated by means of the arm 25 and the resistance unit 26 is connected in series relation with the shunt coil 21. In such manner, the current flowing through the shunt coil may be reduced as desired.

The shunt coil 21 and series coil 19 are now energized from the generator 11, which is operated by the motor 12. Current flows from the positive terminal of the generator through the series coil 19, conductor 27, contactor 18, one blade of the knife switch 15, through the battery 17, one blade of the motor-generator switch 14 and thence to the generator. Another circuit is established from the generator through the series coil 19, shunt coil 21, resistance unit 26 and thence to the negative terminal of the generator 11.

Thus, it will be seen that the coils 19 and 21 are cumulative in energizing the core 22 when the generator 11 is driven by the motor and that current continues to flow in the same direction through the shunt coil. Accordingly, the relay 16 is retained closed.

A control system of this type is adapted for multiple-unit operation of motor vehicles and by providing train lines 28 with suitable jumpers 29, any number of cars may be concurrently controlled. As shown, the negative terminal of each battery is connected through one blade of the battery switch 15 to the negative conductor of the train line 28. The positive conductor of the train line is connected through a conductor 32 to the contact fingers 31 of the contactor 18.

When a plurality of cars are connected together as set forth above, and the battery and motor-generator switches on each vehicle are closed, then all the batteries are connected to train line 28. Consequently, if a battery on any car has not sufficient voltage to effect the operation of the generator on that car at the required pull-in speed, it is aided by a stronger battery on another car.

10 The operation of the control system, described generally, is as follows:

The motor-generator switch 14 and the battery switch 15 are both closed and the coil 30 thus energized. In the manner set forth above, the coil 30 effects the operation of the contactor 18 and the generator 11 is connected across the battery 17. When the generator 11, operating as a motor, rotates at the predetermined pull-in speed the relay 16 functions to close the motor circuit. The generator 11 is then driven by the motor 12 and charges the battery 17.

If the voltage of the battery or batteries is not sufficient to effect the rotation of the motor-generator set at the predetermined pull-in speed, it is impossible to operate the relay contact member 20 and thus the motor circuits cannot be closed. This requires the operator to have the battery charged and so protects the motor-generator set.

Since various changes may be made in the above-described construction and arrangement of parts and different embodiments of the invention may be made without departing from the scope thereof, it is intended that all matter contained in the above description or shown in the accompanying drawing shall be interpreted as illustrative and not in a limiting sense.

40 I claim as my invention:

1. The combination with a motor-generator set, of a main source of power, an auxiliary source of power, means for connecting the generator across the auxiliary source of power to operate the generator as a motor, and means sensitive to the flow of current in the generator disposed to connect the motor across the main source of power when it rotates at a predetermined speed.

50 2. A control system for a motor-generator set comprising a main source of power, an auxiliary source of power, means for connecting the generator across the auxiliary source of power to operate it as a motor, and means sensitive to the flow of current in the generator disposed to connect the motor across the main source of power when it rotates at a predetermined speed, the energization of said motor connecting means being dependent upon the speed of the generator operating as a motor.

3. A control system for a motor-generator set comprising, in combination, a main source of power, an auxiliary source of power, means for connecting the generator across

the auxiliary source of power to operate it as a motor, and a relay disposed to be energized from the auxiliary source of power operable to connect the motor across the main source of power when it rotates at a predetermined speed, the energization of said relay varying with the counter electro-motive force of the generator when operated as a motor.

4. A control system for a motor-generator set comprising, in combination, a main source of power, an auxiliary source of power, means for connecting the generator across the auxiliary source of power to operate it as a motor, and a relay operable to connect, so the motor across the main source of power when it rotates at a predetermined speed, said relay being provided with a plurality of windings adapted for differential energization when the generator is operated as a motor from said auxiliary source of power and cumulative energization when the generator is operated by the motor.

5. A control system for a motor-generator set comprising, in combination, a main source of power, an auxiliary source of power, means for connecting the generator across the auxiliary source of power to operate it as a motor, a relay operable to connect the motor across the main source of power when it rotates at a predetermined speed, said relay being disposed for continually increasing energization as the counter-electromotive force of the generator operated as a motor increases, said relay being adapted to connect the motor across the main source of power when said set rotates at a predetermined speed.

6. A control system for a motor-generator set comprising, in combination, a main source of power, an auxiliary source of power, means for connecting the generator across the auxiliary source of power to operate it as a motor, and a relay operable to connect the motor across the main source of power when it rotates at a predetermined speed, said relay being provided with a series coil and a shunt coil, said series coil being disposed to oppose the shunt coil when the generator operates as a motor and to aid said shunt coil when the generator is driven by the motor.

7. A control system for a motor-generator set comprising, in combination, a main source of power, an auxiliary source of power, means for connecting the generator across the auxiliary source of power to operate it as a motor, a relay operable to connect the motor across the main source of power when it rotates at a predetermined speed, said relay being provided with a series coil and a shunt coil, said series coil being disposed to oppose the shunt coil when the generator operates as a motor and to aid said shunt coil when the generator is driven by

the motor, a resistance unit and means co-operative with said relay to effect the connection of the resistance unit in series relation with said shunt coil.

5. 8. In a control system, in combination, a motor-generator set, a main source of power for normally operating the motor, an auxiliary source of power, means for connecting the generator across the auxiliary source of power to operate it as a motor and means sensitive to the flow of current in the generator disposed to close automatically the motor circuit when the motor rotates at a predetermined speed, said circuit-closing means being connected for energization

by the generator when the motor circuit is closed.

9. The combination with a motor-generator set, of a main source of power, an auxiliary source of power, means for connecting the generator across the auxiliary source of power to operate the generator as a motor and means responsive to changes in current in the generator disposed to connect automatically the motor across the main source of power when it rotates at a predetermined speed.

In testimony whereof, I have hereunto subscribed my name this 22nd day of May, 1925.

WALTER H. SMITH.
